[57] CLAIM

The ornamental design for a 35 MM camera, as shown and described.

DESCRIPTION

FIG. 1 is a top, front and right side perspective view of a 35 MM camera showing my new design with the lens cover closed;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof;

FIG. 8 is a perspective view similar to FIG. 1 with the lens cover open, the flash in extended and the lens in partially extended position; and,

FIG. 9 is a perspective view thereof, with the flash in extended and the lens in fully extended position.
